UNITED STATES PATENT OFFICE.

EMANUEL J. BOYLER, OF NEW HAVEN, CONNECTICUT, ASSIGNOR TO NATHANIEL A. KALETZKY, OF NEW HAVEN, CONNECTICUT.

POWDER PUFF.

1,406,439.

Specification of Letters Patent. Patented Feb. 14, 1922.

Application filed November 8, 1919. Serial No. 336,647.

To all whom it may concern:

Be it known that EMANUEL J. BOYLER, a citizen of the United States, and resident of New Haven, in the county of New Haven and State of Connecticut, has invented certain new and useful Improvements in Powder Puffs, of which the following is a specification.

This invention relates to powder puffs, 10 useful for applying a powder, as a cosmetic or for medicinal purposes, to the skin of the human body.

An object of the invention, among other things, is to provide an efficient article capable of being manufactured at a comparative low cost, and said article is made compact in form and has a reservoir in which the powder to be applied is contained.

According to the present invention, the 20 improved article is composed of a bag, substantially circular in shape, having a restricted open neck at the top in a substantially straight and extended portion thereof. A device consisting of a split tubular clip, 25 of a suitable diameter and length and composed of suitable material, such as celluloid for example, is employed to close said open neck. The said device slides on a defined track formed by raising the edges of said 30 neck and thus tightly closes the same after the article is filled. In its closed position, said device is held in place by engagement with said raised edges and forms a convenient handle.

The bag is made of two substantially circular sections of fabric united together at the edges preferably by means of button hole stitching and being substantially circular in shape, manufacture of the article is 35 considerably facilitated.

The fabric of which the said sections is composed should be porous to some extent to permit contents of the bag to sift there-

through and preferably said fabric is of a fleecy nature and washable. 45

An embodiment of the invention is illustrated in the accompanying drawings wherein—

Figure 1 is an elevation of the complete article; 50

Figure 2 is a sectional view taken on the line 2—2 of Figure 1;

Figure 3 is a fragmentary view of the bag showing the open neck, and

Figure 4 illustrates the device employed 55 for closing said open neck.

Referring to the drawings the circular sections of fabric of which the bag is composed bear the numerals 1 and 1'. 2 represents the continuous circular edge of the article which is strengthened and re-enforced by button hole stitching whereby the edges of the sections 1 and 1' are united. 60

The open neck 3 has its edges re-enforced also by stitching and the split tubular fastening device 4, facilitated by the chamfered corners 5, is engaged with and slides over the edges of the neck 3, bringing said edges tightly together and holding them thus after the bag is filled with powder represented by reference numeral 6. 70

I claim—

A container for toilet powder comprising in combination a bag-like structure of fleecy pervious material provided at the edges 75 about its opening with a reinforcing stitching forming a laterally projecting bead, and a combined closure and handle having resilient jaws adapted slidingly to engage the bag beneath said bead thereby to clamp the 80 bag material and prevent the accidental removal of the closure.

Signed at New Haven in the county of New Haven and State of Connecticut, this 5th day of November, A. D. 1919.

EMANUEL J. BOYLER.
